(57) **CLAIM**

The ornamental design for a vehicle door, as shown and described.

DESCRIPTION

FIG. 1 is a perspective view of a vehicle door mounted and in a closed position;

FIG. 2 is an alternate perspective view with the vehicle door mounted and in an opened position;

FIG. 3 is a side elevational view thereof;

FIG. 4 is a front elevational view thereof;

FIG. 5 is a rear elevational view thereof; and,

FIG. 6 is a top elevational view thereof.

The dashed broken lines illustrate environmental structure that forms no part of the claimed design. The dot dash broken line illustrates a boundary between the claimed and unclaimed structure.
